UNITED STATES PATENT OFFICE.

SPENCER C. CARY, OF BALDWIN, QUEENS COUNTY, NEW YORK, ASSIGNOR TO
WILLIAM H. VANDERBILT, OF BROOKLYN, NEW YORK.

BOX-STRAP.

SPECIFICATION forming part of Letters Patent No. 441,353, dated November 25, 1890.

Application filed June 11, 1890. Serial No. 355,026. (No model.)

To all whom it may concern:

Be it known that I, SPENCER C. CARY, of Baldwin, county of Queens, State of New York, a citizen of the United States, have invented certain new and useful Improvements 5 in Metal Box-Straps, of which the following is a full, clear, and exact description, reference being had to the accompanying drawings, forming part of this specification.

10 My invention relates to metal box-straps; and it consists in a metal band for box-straps of requisite width cut with thinned or beveled edges from an edge of a metal sheet, and preferably united endwise to constitute a strap 15 of indefinite length, with the side edges thereof curled inward upon themselves, respectively, and pressed closely to the strap-body, substantially as and for the purpose herein-after set forth.

20 Figure 1 is a view in plan of a metal box-strap containing my invention, and Fig. 2 is a cross-section of the same on the line $x x$, Fig. 1.

In fabricating my improved box-strap bands or strips A, of suitable width, are cut 25 or slit from an edge of a sheet of metal, and these bands or strips are then preferably jointed together endwise, as illustrated in Fig. 1, being united at their overlapped ends 30 by rivets or eyelets a and constituting a continuous metal strap of indefinite length.

In cutting the bands or strips from an edge 35 of a metal sheet the action of the slitting-knife in passing through the sheet bends or deflects the metal along the line of the cut so as to cause the edges made on the bands by the cut to project somewhat beyond the under face of the band and to be drawn or pressed by the knife-edge to a thinness or bevel and 40 consequent sharpness, which is objectionable in a box-strap, owing to the fact that such sharp side edges are liable to wound or injure the hands of the users of the straps. In completing my invention, therefore, I curl or roll 45 the side edges of the strap over and upon themselves, respectively, and press them closely into contact with the body of the strap. This may be effected by passing the strap composed of the endwise-jointed bands, or 50 the bands individually before they are jointed together endwise to constitute the strap, be-

tween a pair or pairs of circumferentially-grooved rollers, with the sharp edges formed on the strap by the slitting-knife, as set forth, seated in said circumferential grooves, said 55 rollers being adapted to press upon said sharp edges as the strap travels between them, so that the sharp edges will be curled over upon themselves, respectively, and pressed closely to the strap-body. This essential feature of 60 my improved metal strap is clearly illustrated in Fig. 2, the curled edges of the strap being shown therein at a', pressed closely to the strap-body along said edges. In the box-strap thus formed the side edges may be made 65 rounded and smooth, the sharp edges formed by the cut of the slitting-knife being bent or turned inward, as set forth, upon the strap, so that the completed strap may be handled and used without danger of injury to the 70 hands of the users. Furthermore, my described metal box-strap may be coiled into a helix flatwise upon a suitable spool or holder and in this condition be transported and be 75 unwound from its spool in desired lengths at the place of use.

I am aware that metal box-straps have been heretofore fabricated by cutting bands or strips of suitable width from a metal sheet and uniting such bands or strips endwise to 80 constitute a strap of indefinite length; and hence I make no claim herein, broadly, to such a metal strap.

I am also aware that metal bands have had 85 their side edges bent or turned over upon and pressed to a face of the strap, and I make no claim herein to a strap having edges thus turned over and pressed to the strap-face. Straps having edges thus formed are thereby thickened at their edges and are incapable of 90 being coiled upon a spool or reel, owing to the increased stiffness given to the strap edges by the said bend and owing to the buckling up or wrinkling of the turned-over edges when the strap is bent upon itself flatwise. 95 In my improved strap the thinned and sharp side edges of the bands formed by the knife cuts in slitting the bands from the metal sheet are curled inward upon themselves, respectively, and pressed to the body of the bands 100 at and upon and along said edges, and it is to a strap comprising this essential feature

which affords the advantages herein recited that I make claim herein.

I do not claim herein the method of making metal box-straps, which consists in cutting metal bands or strips of suitable width from an edge of a sheet of metal, jointing said bands or strips together endwise to constitute a metal strap of indefinite length, and, either before or after said bands or strips are thus jointed endwise, rolling or curling the side edges thereof inwardly over and upon themselves, respectively, and pressing them to the band-body at and upon and along the side edges thereof; nor do I claim herein the preferable mechanism by means of which I thus roll or curl the band edges inwardly upon themselves and press them to the band-body at and upon and along the side edges thereof,

as such method and mechanism are the subject-matter of claims in a separate application for Letters Patent filed by me simultaneously herewith, Serial No. 355,027.

What I claim as my invention, and desire to secure by Letters Patent, is—

A metal band for box-straps, cut with thinned or beveled edges from an edge of a sheet of metal and having said thinned or beveled side edges curled inward upon themselves, respectively, and pressed closely to the band-body at, upon, and along said side edges thereof, substantially as and for the purpose set forth.

SPENCER C. CARY.
